(57) **CLAIM**

The ornamental design for a dashboard for paver, as shown and described.

DESCRIPTION

FIG. 1 is a right front perspective view of a dashboard for paver showing my new design;

FIG. 2 is a top perspective view thereof;

FIG. 3 is a right rear perspective view thereof;

FIG. 4 is a bottom perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is a top plan view thereof; and,

FIG. 10 is a bottom plan view thereof.

1 Claim, 10 Drawing Sheets---
